UNITED STATES PATENT OFFICE.

CHARLES W. T. DAVIES, OF NEW YORK, N. Y.

BIFURCATED UNDERGARMENT.

1,094,981.

Specification of Letters Patent. Patented Apr. 28, 1914.

Application filed February 12, 1914. Serial No. 818,363.

To all whom it may concern:

Be it known that I, CHARLES W. T. DAVIES, a subject of the King of Great Britain, residing at New York, county of New York, 5 and State of New York, have invented certain new and useful Improvements in Bifurcated Undergarments, of which the following is a specification.

This invention relates to bifurcated undergarments.

The present invention, which is adapted for embodiment in drawers, combination underwear, or union suits, has for its object the provision of an improved posterior construction for the drawers, whereby there is provided a laterally movable or shiftable seat section which may be quickly and easily opened or closed while hanging straight down, thereby obviating the necessity of 15 swinging a large seat flap and the difficulty of restoring it to normal closed position which is incident to those drawers, combination garments or union suits employing a split leg.

25 My invention does not disturb the usual or natural "hang" or "set" of the bifurcated garment, but at the same time it possesses the advantages of affording a large opening in the posterior portion of the drawers, 30 when the latter are opened, by sliding the movable portion of the seat, and the relation of the parts is such that the user does not have to manipulate or move a flap about from point to point in an effort to button or 35 fasten it when it is to be closed. With my invention, merely grasping the shiftable section of the seat and sliding it to and fro naturally and automatically, as it were, positions it for fastening or buttoning when 40 being closed and for locating it properly to adequately open the seat of the drawers when desired.

In carrying out my invention in either 45 drawers, combination suit, or union suit, I provide an opening extending upwardly and downwardly in one of the legs of the undergarment and slidably dispose or hang a portion of the seat of the drawers, preferably for a distance of approximately one-quarter 50 of the circumference of the undergarment at its waist, on a waist-band of the undergarment. Preferably one of the legs of the bifurcated garment is open clear through the lower end thereof from a point in the 55 region of the waist portion. One or more fastening devices, such as a button and but-

tonhole, are provided for securing the slide- 60 able seat section to the split leg. I may provide the split leg and slideable seat portion with overlapped parts. When the invention 65 is embodied in a combination or union suit, the shirt or body portion thereof may be provided with a skirt or tail extending under or over the waist-band which supports the slideable seat section. If the invention is 70 carried out in a combination or union suit, the undergarment may be provided with a front opening, having suitable fasteners, extending from the neck to a point near the crotch thereof.

If the invention is embodied in drawers, 75 they may have a suitable fly. Whether the invention be carried out in drawers only or in a combination or union suit, it is only necessary for a sufficient length of waist- 80 band to be provided such as will afford a support for the suspension of the slideable section of the seat, but the waist-band may extend entirely around the waist portion of the undergarment, which is the preferred 85 construction.

I am aware that modification may be resorted to in carrying out the invention in drawers, combination and union suits and the embodiments of the invention herein set 85 forth and disclosed in the drawings are, therefore, to be considered as illustrative, rather than restrictive, of the scope of the invention.

In the accompanying drawings: Figure 1 90 is a front perspective of a pair of drawers embodying the invention, the movable seat section being in partially open condition; Fig. 2, a rear elevation of Fig. 1; Fig. 3, a rear elevation of a pair of drawers having 95 the invention, where the seat is shown closed; Fig. 4, a rear view of the invention applied to a union suit, the seat being closed; Fig. 5, a view like Fig. 4 with the seat open. Figs. 6 and 7, rear views of 100 drawers embodying modifications; Figs. 8 and 9, front views of drawers showing other modifications; and Fig. 10, a view of the drawers of Fig. 9, drawn back.

Referring to Figs. 1, 2 and 3, which show 105 a pair of drawers provided with the invention, the respective legs of the drawers are shown at 1 and 2, the former constituting a complete leg having a rear or posterior portion 3 completely closed except at its top 110 and lower end. Any suitable opening or fly 4 may be provided. The leg 2 has as its

rear or posterior part a slidable or laterally movable seat and leg 5 which is slidably mounted at its upper end on a tape or waist-band 6 in the manner that a curtain is suspended from its pole except that the band 6 is of cloth and is suitably pliable or flexible, as with any waist-band, and that the upper part of the seat section 5 is looped around the band 6 in a loose and slidable manner, as shown at 7. The waist-band 6 is preferably of at least a length equal to one-quarter of the circumference of the garment at the waist portion thereof, but I do not limit myself to this extent, as it may be greater or less. It is not absolutely necessary that the same waist-band 6 continue around the entire undergarment or that the same waistband be used as a continuation of the band 6, even if a complete waist-band be employed. Preferably, however, the waist-band 6 is made in one continuous piece extending completely around the garment as shown at 6^a. However constructed, all parts of the drawers except the part 7, are stitched or secured to the waist-band as, for instance, at 8. One of the leg sections 2, or 5, may be provided with a vertical strip or band 9 to overlap the edge 10 of the other part and suitable fastening devices such as buttons 11 and buttonholes 12, are employed to connect the edge of the slidable seat section 5 to the remaining portion 1 of that leg. The split or open portion 13 thus provided is preferably located at the extreme outside 35 of the leg and extends from the top entirely through the lower end 14 thereof.

The embodiment of the invention shown in Figs. 4 and 5 is the same as that previously described in connection with Figs. 1, 2 and 40 3, except that there is added a shirt or body portion 15, sleeved or sleeveless, which is secured to the waist-band 6^a around the entire circumference thereof but is loose or separated from the band 6 at 16 from the point 17 to the point 18 and extends down behind said band 6 in the form of a tail or skirt 19 which may or may not be connected to the front 2 along the line 20 and under the strip 9.

50 The union suit shown in Figs. 4 and 5 has a closed crotch and a front opening 21, shown by dotted lines, extending from the neck to a point near the closed crotch in both the shirt 15 and drawers.

55 The invention may be embodied in a combination suit having shirt and drawers detachably connected together by any suitable means.

When the nether garment is connected 60 either permanently, as a union suit, or detachably, as a combination garment, to the upper garment, it is immaterial whether it is connected thereto on the inner or outer surface of the upper garment, so long as the suspending band 6 is disconnected from the

body of the garment for the distance to be utilized for the sliding operation. Also, while I have shown in Figs. 1 to 5, the starting point of the sliding seat on the outside of the leg only, it may be arranged to start 70 at any point of the leg, either at the rear or in front, and in fact, in each leg, if necessary, independently of the other leg.

While I have shown the suspending band applied to only one upper edge of a leg section, the upper edge of the other leg section may also be mounted on a suspending band, to slide along in the opposite direction from the other, and thus still further increase the space between the sections, in the nature of 80 a pair of curtains, and leave the whole of one leg, from hip to foot, exposed.

Figs. 6 to 10 illustrate certain of the modifications just referred to.

In Fig. 6, the leg is split in its rear portion in a line running toward the inside of the leg as at 13^a, there being provided a triangular flap or seat section 22 which is slidably on the suspending band 6 and adapted for securing by a fastening device 23. 90 The flap 22 may be attached to the inside of the leg at 24.

In Fig. 7, the split 13^b extends in general up and down direction in the rear of the leg and terminates at 25, there being provided a seat flap 26 which is slidable on band 6. Fastening devices 27 are provided for the flap 26.

The drawers of Fig. 8 have the split 13^c in the front of the leg. The band 6 comprehends substantially one-half of the circumference of the waist of the drawers and constitutes a suspending device for its entire length at one side of the garment, between the points 28 and 29, the other side 30 of the waist band being secured to the closed drawers leg 31. The entire leg section 32 is slidably suspended from band 6 and adapted to slide rearwardly toward the point 28, while the front section 33 slides partially across the front of the drawers toward the point 29, somewhat in the manner illustrated in Fig. 10, which latter figure, however, specifically illustrates the operation of the drawers of Fig. 9.

In the drawers of Fig. 9, the slit 34 at the outside of the leg is also the closure of the drawers, a front closure being unnecessary; a fly 35 is provided. The sections 36 and 37 are fastened by buttons and buttonholes 38. The suspending band 6 is formed in two sections 39 and 40 detachably connected together at 41. The sections 36 and 37 slide in opposite directions, exposing the whole of one leg to a point below the crotch, as shown in Fig. 10. Wherever the split is provided, it is immaterial which of the edges of the split overlaps or underlaps the other edge thereof.

Having thus described my invention, what 130

I claim as new and desire to secure by Letters Patent, is:—

1. A bifurcated undergarment having a laterally movable seat section slidably suspended at its upper part.
2. A bifurcated undergarment having at least one of its legs split in a general up and down direction and provided with a laterally movable seat section whose free edge is defined by said split, said seat section being slidably suspended at its upper part.
3. A bifurcated undergarment having one of its legs split in a general up and down direction clear through its lower end and provided with a laterally and bodily movable seat section whose free side and bottom edges are defined by the said split and by the

lower end of the leg, said seat section being slidably suspended at its upper part.

4. A bifurcated undergarment having a laterally arranged suspending band or member and a movable seat section whose upper part is slideable on said band.

5. A bifurcated undergarment having a laterally arranged suspending band or member, a split leg, and a movable seat section whose upper part is slideable on said band and which freely depends from said band.

In testimony whereof, I hereunto affix my signature in presence of two witnesses.

CHARLES W. T. DAVIES.
